(57) **CLAIM**

The ornamental design for an aircraft side stick controller, as
shown and described.

DESCRIPTION

The patent or application file contains a least one drawing
executed in color. Copies of this patent or patent application
publication with color drawing(s) will be provided by the
Office upon request and payment of the necessary fee.

FIG. 1 is a front perspective view of an aircraft side stick
controller showing our new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a front perspective view thereof in an aircraft cockpit.
The broken lines illustrate structure and environment that
form no part of the claimed design.
